ELECTRIC TOOTH BRUSH

Melvin H. Boldt, Glenview, Ill., assignor to Schick Electric Inc., Lancaster, Pa., a corporation of Delaware

Filed July 7, 1967, Ser. No. 7,731

Term of patent 14 years

(Cl. D9—2)

FIG.1

FIG.2

FIG. 3

FIG. 4

FIG. 5

FIG. 1 is a front perspective view of an electric toothbrush showing my new design;

FIG. 2 is an elevational view thereof showing the side opposite to that as viewed in FIG. 1;

FIG. 3 is a rear elevational view thereof;

FIG. 4 is a top plan view thereof; and

FIG. 5 is a bottom plan view thereof.

The dominant features of my design reside in the portions shown in full lines on the drawing.

I claim:

The ornamental design for an electric tooth brush, substantially as shown and described.
